UNITED STATES PATENT OFFICE

2,440,385

TOOTHBRUSH HOLDER

Charles F. Schulte, Columbus, Ohio

Application March 2, 1946, Serial No. 651,541

3 Claims. (Cl. 211—65)

1

My invention relates to holders for the detachable reception of articles, and more specifically to holders of the type which support a plurality of articles to be used in a set rotational order.

The present form of my invention constitutes a holder for tooth brushes, but it will be manifest that the same is adaptable for use with various other articles, such as cutting tools, drill bits, etc., where rotational usage of the articles is desired or required.

It is therefore the general object of my invention to provide a holder for the detachable reception of a plurality of articles which permits of the removal of the articles only in a set rotational order.

It is another object of my invention to provide a holder of this character which is structurally simple and free of a multiplicity of moving parts and is thereby inexpensive to manufacture.

It is still a further object of my invention to provide a holder of this character which provides means whereby the rotational order of the articles, supported by the holder, may not be unintentionally changed or interrupted before removal therefrom.

For a further understanding of my invention, reference is made to the following description and accompanying drawing, wherein:

Fig. 1 is a perspective view of my improved tooth brush holder;

Fig. 2 is a front elevational view thereof;

Fig. 3 is a bottom elevational view;

Fig. 4 is a perspective view of a modified form of my invention, wherein the holder is adapted for two sets of tooth brushes to be removed in rotational order;

Fig. 5 is a front elevational view of this modified form;

Fig. 6 is a bottom view thereof.

With reference to the drawings, it will be seen that my improved holder comprises a U-shaped body 10 formed of a suitable material such as one of the many commercial plastics, or of a semi-resilient metal. The body 10 is formed with a pair of inturned flanges 11 having adjoining resiliently separable edges or jaws 12, the latter being recessed so as to provide a rectangular opening 13 adapted to receive the handles of tooth brushes supported by the flanges of the holder.

At the entrance or receiving end 14 of the holder, the outer edges of the jaws 12 are rounded to constitute a relieved or indented portion 15 which permits of relative separation between the

2

jaws when the handle of a tooth brush is forced therebetween and toward the opening 13. At the opposite or removal end 16, the outer edges of the jaws form a relatively straight smooth surface to prevent such relative separation between the jaws.

At the removal end of the opening 13, the jaws are also rounded to provide another indented portion 17 which allows, upon the removal of the tooth brush handle, the separation of the jaws. The opposite end of the opening, at the juncture of the jaws is relatively straight and smooth so as to prevent the separation of the jaws.

Thus it will be seen that a tooth brush handle may be inserted between the jaws only from the entrance side 14, and that the brush may be removed from the opening only by moving it toward the removal or discharge side 16.

In use, the holder supports two or more tooth brushes which are inserted through the receiving end 14 and are held by the flanges within the opening 13. As one of the brushes is taken from the removal side for use, it will be manifest that it can only be replaced within the holder by inserting it in the receiving side, thus presenting the unused brush to the removal side for the next usage. This is a particularly desirable feature, in that the brushes are, in this manner, used in rotation, and under normal usage are allowed sufficient time for drying. Also, it has been found that by using two brushes in rotation, the useful life of each individual brush is greatly increased.

Figs. 4 through 6 disclose a modified form of my improved holder incorporating the same rotational removal feature. In this form, the holder is adapted for two sets of brushes. The holder bodies 10 are spaced one from the other and are connected by an integral rear wall 18 extending between the two units.

It will be seen that my improved holder may be easily constructed for family use by the simple addition of several more of the above supporting bodies.

The single set holder, as shown in Figs. 1, 2 and 3, is adapted for attachment to a wall or other flat surface by driving a screw through the screw holes 19 located in the rear wall of the body. To allow easy access to these screws, I have provided a pair of relatively enlarged access apertures 20 through which the head of a screw driver may be inserted for driving contact with the screws. In the double or plural form, as in Figs. 4, 5 and 6, screw holes 19 are provided in the connecting rear wall 18, and are easily accessible

by nature of the spaced relation of the holder bodies.

In view of the foregoing, it will be seen that my improved tooth brush holder provides a structurally simple and positive means for supporting several tooth brushes, and at the same time serves as a device whereby the brushes may only be inserted and removed from the holder in a given rotational order. Further, my invention provides a sanitary protective covering for the brushing head and allows ample ventilation necessary for drying by the nature of its open ends. My invention is characterized by its economy of manufacture, and its positive operation.

While I have disclosed what I now deem to be preferred forms of my invention, it will be manifest that minor variations, as to details of construction and design, may be later accomplished without departing from the spirit of the invention or the scope of the following claims.

I claim:

1. An article holder comprising a body formed to include a pair of horizontally aligned resiliently separable jaws, the latter having adjoining edges, at least one of said edges being recessed to provide an opening for the reception of handles of articles to be supported by said jaws, said edges at the article entrance end of the jaws being relieved to permit of relative separation between said jaws when a handle of an article is forced therebetween and toward said opening, the opposite or article-removal end of the jaws being unrelieved to prevent the insertion of an article handle therebetween, and one end only of said opening at the article-removal side thereof being relieved to permit of the passage of an article during removal thereof from the holder through the separation of the jaws.

2. An article holder comprising a U-shaped body formed to include a pair of inturned horizontally aligned resiliently separable jaws having adjoining edges, said edges being recessed to provide an opening for the reception of handles of articles to be supported by said jaws, said edges

being relieved at the article entrance end of the jaws to permit of relative separation between said jaws when a handle of an article is forced therebetween and toward said opening, the opposite or article removal end of the jaws being unrelieved to prevent the insertion of an article handle therebetween, and one end only of said opening at the article-removal side thereof being relieved to permit of the passage of an article during removal thereof from the holder through the separation of the jaws.

3. An article holder comprising a tunnel-shaped body formed with a pair of inturned horizontally aligned flanges, the internal edges of said flanges forming a plurality of resiliently separable adjoining jaws, said jaws being recessed to provide an opening for the reception of handles of articles to be supported by said flanges, said edges at the article entrance end of the body being relieved to permit of relative separation between said jaws when a handle of an article is forced therebetween and toward said opening, the edges at the article-removal end of said body being unrelieved to prevent the insertion of an article handle therebetween, and one end only of said opening at the article-removal side thereof being relieved to permit of the passage of an article during removal thereof from the holder through the separation of the jaws.
